EYEBROW PENCIL

John J. Woessner, Maspeth, N. Y., assignor to
Eberhard Faber Pencil Co., a corporation of
New York

Application April 11, 1936, Serial No. 73,816

2 Claims. (Cl. 120—18)

This invention relates in general to holders for marking materials, and more particularly to an eyebrow pencil wherein a cylinder of marking composition is mounted in a casing which serves 5 as a handle for applying the composition to the eyebrow.

One object of the invention is to provide a novel and improved pencil of the character described which shall comprise a barrel or casing 10 having a holder for a cylinder of the marking composition and means for projecting and retracting the cylinder from and into the casing at the will of the user so that the material may be completely housed within the casing to protect it against contact with other articles, such 15 as a handbag, when the pencil is out of use, and the marking composition may be projected from the casing when it is desired to apply it to the eyebrows.

Another object is to provide such a pencil embodying novel and improved features of construction whereby the pencil shall be simple and inexpensive in construction and reliable and durable in operation.

Other objects, advantages and results of the invention will appear from the following description when read in conjunction with the accompanying drawing wherein

Figure 1 is a side elevation on a greatly enlarged scale of a pencil embodying the invention.

Figure 2 is a longitudinal sectional view through the barrel of the pencil with portions of the operating mechanism shown in side elevation.

Figure 3 is a complete longitudinal sectional view through the pencil.

Figure 4 is a detached side elevation of the guide tube.

Figure 5 is a detached side elevation of the holder for the marking composition, and

Figure 6 is a transverse sectional view on the line 6—6 of Figure 2.

In said drawing, corresponding and like parts are designated throughout the several views by the same reference characters, and the reference 45 character A designates the barrel of the pencil which is open at both ends and has one end tapered at 1 through which the cylinder of marking composition 2 is projected.

Within the barrel A is a guide tube 3 which is 50 shown as consisting of a single sheet of resilient material rolled into tubular form of a diameter slightly greater than that of the interior diameter of the barrel A, and preferably said guide tube is secured in the barrel by frictional contact between the tube and the barrel caused by

the contraction of the tube as it is inserted in the barrel and the consequent inherent expanding resiliency of the guide tube, although the tube may be secured in the barrel in any other suitable way. The edges of the sheet of material forming the tube are in spaced and approximately parallel relation and the edge portions 4 are preferably turned inwardly so as to have a chordal relation to the interior walls of the barrel as clearly shown in Figure 6.

Within the guide tube is mounted a helical coil 5 that is rotatable but longitudinally immovable in the barrel. As shown, one end of the coil is fitted into a hollow plug or cap 6 which has an inwardly projecting rib 7 to frictionally 10 compress the coil and connect it to the plug so that the coil will rotate with the plug. The plug is rotatably but longitudinally immovably connected to the barrel by a rib 8 on the inner surface of the barrel seated in a circumferential 15 groove 9 on the exterior of the plug.

Within the helical coil is disposed a holder 10 for the cylinder 2 of marking composition. This holder is shown as consisting of a single sheet of material rolled to form a split tube and having two pairs of lugs 11 projecting laterally therefrom. As shown, each lug 11 of each pair is integral with and projects from one edge of the slit 12 in the holder and in juxtaposition or side-by-side relation with the lug on the other edge, 20 and each pair of lugs projects through the space between two adjacent convolutions of the helical coil and into the space or slot provided by the edge portions 4 of the guide tube 3. The cylinder 2 of marking composition is inserted into the 25 holder and frictionally held therein by the inherent contracting resiliency of the split tube holder.

With this construction, the holder 10 may move longitudinally of the guide tube and helical coil 40 but is held against rotation by the lugs 11 in the slot between the edges of the guide tube, and upon rotation of the helical coil, for example by holding the barrel in one hand and rotating the plug 6 with the other, the holder 10 will be moved longitudinally of the barrel so as to project or retract the cylinder 2 of marking composition from or into the barrel, respectively.

During this operation, the lugs 11 of each pair 45 mutually reinforce each other so as to restrain 50 any tendency to bending of either lug upon tendency to relative rotation of the holder 10 and the guide tube, and the edges of the lugs provide extended bearing surfaces to engage the convolutions of the helical coil. As shown, the lugs of 55

each pair are preferably slightly spaced apart so as to snugly engage the edges of the slot in the guide tube and to yield toward each other to compensate for irregularities in said edges of the slot or the spacing thereof and prevent binding or jamming of the parts. Also, the two pairs of lugs cooperate to restrain any lateral swinging of the holder in the coil and thereby prevent catching of the ends of the holder on the edges of the convolutions of the coils.

The guide tube 3 and holder 10 being formed of single sheets of metal and rolled into tubular form, are simple and inexpensive, and the particular form of the guide tube and manner of securing it in the barrel enables easy, quick and inexpensive assembly of the parts. The chordal relation of the edge portions 4 of the guide tube to the inner walls of the barrel insure proper engagement of the lugs 11 with the guide tube and reduce the possibility of the lugs slipping out of the slot formed by said edge portions in the guide tube.

Having thus described my invention what I claim is:

1. A pencil comprising a barrel, a single sheet of metal rolled to form a guide tube secured in said barrel and having its edges in parallel and spaced relation, the portions of said tube at the edges of said slot being disposed in approximately chordal relation to the inner walls of said barrel, a helical coil rotatable but longitudinally immovable in said tube, and a holder for marking material slideable longitudinally in said helical coil and having a lateral lug extending between two adjacent convolutions in said coil and slideable longitudinally of and between said edges of said sheet forming the guide tube. 5 10

2. The pencil set forth in claim 1 wherein said sheet forming the guide tube is of resilient material and held in position in said barrel by frictional engagement between the tube and barrel caused by the inherent expanding resiliency of the guide tube. 15 20

JOHN J. WOESSNER.
